[57] CLAIM

The ornamental design for a soap bar dispenser and holder, as shown and described.

DESCRIPTION

FIG. 1 is a top, front, and left side perspective view of a soap bar dispenser and holder showing our new design;

FIG. 2 is a front elevational view thereof, with the broken-line disclosure of a soap bar being for illustrative purposes only and forming no part of the claimed design;

FIG. 3 is a right side elevational view thereof;

FIG. 4 is a rear elevational view thereof;

FIG. 5 is a top plan view thereof; and,

FIG. 6 is a bottom plan view thereof.

FIG. 2

FIG. 1

FIG. 4

FIG. 3

FIG. 5

FIG. 6
